(57) **CLAIM**

The ornamental design for a set of gemstones in an arrangement, as shown and described.

DESCRIPTION

FIG. 1 is an isometric view of a set of gemstones in an arrangement;

FIG. 2 is a top view of the set of gemstones in an arrangement shown in FIG. 1; and,

FIG. 3 is a side view of the gems shown in FIG. 1 looking toward the stone at the bottom of the arrangement in FIG. 2, which is identical to the side view of the gems shown in FIG. 1 looking toward the stone abutting and to the left of the stone at the bottom of the arrangement in FIG. 2.
